CLAIM

The ornamental design for a hybrid grill, as shown and described.

DESCRIPTION

FIG. 1 is a top front isometric view of a hybrid grill showing the design.

FIG. 2 bottom rear isometric view of the hybrid grill of FIG. 1.

FIG. 3 is front elevation view of the hybrid grill of FIG. 1.

FIG. 4 is a rear elevation view of the hybrid grill of FIG. 1.

FIG. 5 is a left elevation view of the hybrid grill of FIG. 1.

FIG. 6 is a right elevation view of the hybrid grill of FIG. 1.

FIG. 7 is a top plan view of the hybrid grill of FIG. 1; and, FIG. 8 is a bottom plan view of the hybrid grill of FIG. 1. The dashed lines in the drawings illustrate portions of the hybrid grill that form no part of the claimed design. The shading lines shown in the drawings represent the approximate three-dimensional contour of the claimed design and are not intended to indicate surface decoration.
